UNITED STATES PATENT OFFICE.

FRANK GETTYS SCOTT, OF NEW ORLEANS, LOUISIANA.

OPERATING MECHANISM FOR ICE-CREAM FREEZERS.

Application filed October 20, 1924. Serial No. 744,752.

This invention relates in general to ice cream freezers, and more particularly to an improved operating mechanism and mounting and holding means for the ice cream 5 freezer.

The object of the present invention is to provide a device of this character whereby the person operating the ice cream freezer may utilize an easy back and forth or oscillating movement to impart a continuous rotary movement to the dasher shaft of the ice cream freezer.

A further object is the provision of a device of this character in which the parts may 15 be easily assembled and disassembled and yet when assembled provides a strong and rigid structure which is smooth, easy and noiseless in its operation.

A further object is the provision of a device of this character which is of simple and durable construction, reliable and efficient in operation and easy and comparatively inexpensive to manufacture.

Other objects and advantages reside in 25 certain novel features of the construction, arrangement and combination of parts which will be hereinafter more fully described and particularly pointed out in the appended 30 claim, reference being had to the accompanying drawings, forming a part of this specification, and in which:

Figure 1 is a view partly in section and partly in elevation showing one embodiment 35 of the invention,

Figure 2 is a view in section taken approximately on the line 2-2 of Figure 1,

Figure 3 is a detail view in section on the line 3-3 of Figure 1 and showing the structure of the pawls employed,

Figure 4 is a detail perspective view of 40 one of the lugs of the tub for holding the can in place,

Figure 5 is a detail view in plan of the rocker,

Figure 6 is a detail view in plan of the 45 frame and its attaching means,

Figure 7 is a detail view illustrating the metal strips of the can which co-act with the lugs in the tub for holding the can against 50 angular movement,

Figure 8 is a detail perspective view of one of the fixed attaching lugs on the tub for the frame of the operating mechanism, and

Figure 9 is a similar view of the swingable 55 attaching lug employed.

Referring to the drawings, the numeral 1

designates an ice cream freezer tub which may be of conventional form, and which includes a cylindrical body 2 and a bottom 3. The tub 1 is designed to receive the usual can 4 and in order to hold the can 4 against angular movement in the tub a number of strips 5 are fixed to the bottom of the can and have their outer portions 6 projecting beyond the periphery of the can (see Fig. 65 7). The portions 6 of the strips 5 are designed to engage lugs 7, fastened, as at 8, to the bottom 3 of the tub.

The dasher shaft 10 operates in the can 4 in the usual manner and carries the usual 70 paddles 11. At its upper end the dasher shaft 10 is provided with a tapered and polygonally formed portion 12. A frame, designated generally at 13, is designed for supporting the operating mechanism for the 75 dasher shaft 10 and as shown to advantage in Figs. 1 and 6, this frame consists of a bar of metal extended diametrically of the tub and having arcuate extensions 14 at its ends designed to rest on portions of the top of 80 the cylindrical body 2 of the tub. The arcuate extensions 14 are provided with lips 15, three of which co-act with fixed L-shaped lugs 16 fastened to the outside of the tub. It is to be understood that the frame 13 may 85 be placed on the top of the tub with the lips 15 angularly spaced from the circumferentially extending portion 17 of the L-shaped lug 16 and that the frame 13 may then be rotated to bring the lips 15 beneath the circumferentially extending portions 17 of the lugs 16 (see Fig. 8). A swinging L-shaped lug 18 is also provided and is pivotally mounted, as at 19, on the cylindrical body 2 of the tub. The lug 18 may be swung out of the 90 way of its lip 15 or it may be swung over the lip 15 to hold the same in position. A pivoted locking lug 20 is provided for securing the swinging lug 18 in engagement with its lip 15.

The frame 13 is provided at its center with an opening 21 up through which the dasher shaft 10 extends. On each side of the central opening 21 the frame 13 is formed with seats 22 on which the lower 105 ends 23 of an inverted V-shaped bracket 24 rest and to which the lower ends 23 of the bracket are secured by bolts and nuts 25.

A beveled pinion 26 is provided and is formed with a polygonally-shaped and tapered socket 27 into which the tapered and polygonally-shaped upper end 12 of the

dasher shaft 10 is snugly fitted, whereby the pinion 26 is movably fixed to the dasher shaft. A stud 28 is integrally formed with the pinion 26 and is rotatably fitted in a socket 29 provided on the underside of the bracket 24. In order to hold the pinion against accidental displacement when the frame 13 is lifted off the dasher shaft, the pinion 26 is formed with a depending annular flange 30 which is rotatably fitted within an upstanding annular flange 31 provided on the frame 13. It is not necessary that these flanges 30 and 31 provide a bearing since the pinion 26 is carried by the dasher shaft which has the usual bearing in the bottom of the can 4 and in the opening 21 through 13.

An axle 32 is mounted in the uppermost portion of the bracket 24 and extends on each side of the bracket. As clearly shown in Fig. 2 a pair of oppositely disposed bevel gears 33 are mounted on the opposite ends of the axle 32, one gear 33 being arranged on one side of the bracket 24 and adjacent one end of the axle and the other gear being arranged on the opposite side of the bracket and adjacent the opposite end of the axle. Nuts 34 are threaded onto the axle 32 to prevent accidental displacement of the gears off the ends of the axle. The teeth of the gears 33 are meshed with the teeth of the pinion 26. A circular series of ratchet teeth 35 are provided on each gear 33, each ratchet tooth of each series having a beveled face 35^a and a flat face 35^b. The ratchet teeth 35 are located on the confronting faces of the gears and are exactly opposite each other. Due to the opposite arrangement of the gears the ratchet teeth of one gear wheel are reversed with respect to the ratchet teeth of the other gear wheel.

A rocker, designated generally at 36, is provided and includes two diverging arms 37 which are fulcrumed at their juncture on the axle 32 in between the gears 33. Preferably the rocker includes a pair of spaced metallic plates 38 (see Fig. 5) of approximately V-shaped form and a pair of wooden handles 39 arranged in between the plates 38 and secured thereto. The handles 39 project beyond the plates at their outer ends and terminate at their inner ends at a substantial distance from the centers of the plates so that there is an opening between the intermediate portions of the plates 38. The plates 38 at their centers are fulcrumed on the axle 32, the plates having openings 40 in which the axle 32 is rotatably fitted. As shown in Fig. 2 the plates 38 are on the opposite sides of the bracket 24. Spacing washers 41 are provided between the plates 38 and the gears 33. At equal distances from the center or axis of the rocker, cross

arms 42 extend transversely between the plates 38. Each cross arm may be integrally formed with one plate and may have a tenon 43 at its other end inserted in a socket 44 in the other plate (see Fig. 3). Transversely and oppositely disposed pawls 45 are provided and are pivotally mounted on the cross arms 42. Each pawl includes a body portion 46 having a pair of ears 47 adjacent one end, the ears 47 straddling the cross arm 42 on which the pawl is mounted and being pivotally connected to such cross arm by a pivot pin 48. The body portion of each pawl 46 is in between the ears and rearwardly of the body portion is cut-away, as at 49, to provide the clearance necessary to permit the pawl to rock or swing. The end of the pawl remote from the pivot pin 48 is reduced and beveled, as at 50, and this reduced and beveled end is designed to co-act with the ratchet teeth for which the pawl is provided.

With this arrangement when the device has been assembled with an ice cream can, tub and dasher shaft, as shown in Fig. 1 and the handles 39 or either of them grasped and rocked up and down the dasher shaft 10 will be continuously rotated in one direction for when one of the pawls 45 is playing idly down over the beveled faces 35^a of its teeth the other pawl is engaged with a flat face 35^b of a tooth of one of the gears 33 and consequently rotates the pinion 26 and shaft 10. The other gear is rotated from the pinion 26 but moves idly on the axle 32. In this way the pawls 45 will alternately drive the gears 33 to rotate the pinion 26 and the shaft 10 continuously in one direction.

I claim:

In an operating mechanism for ice cream freezers, a bracket, a beveled pinion associated with the bracket, an axle mounted on the bracket, a pair of oppositely disposed beveled gears freely rotatable on the axle and meshed with the pinion, a series of ratchet teeth on each gear, the ratchet teeth being opposite each other and being located on the confronting faces of the gears, the ratchet teeth of one gear being reversed with respect to the ratchet teeth of the other, a rocker fulcrumed on the axle between the gears and having diverging arms made up at their centers by spaced plates, transversely extending cross arms carried by the spaced plates, and a pawl mounted on each cross arm for each series of ratchet teeth, each pawl also extending transversely between the gears and having a reduced and beveled extension co-operable with the teeth of the ratchet with which it co-acts.

FRANK GETTYS SCOTT.
